UNITED STATES PATENT OFFICE.

JACOB H. LEIST, OF PORTLAND, OREGON.

GASIFIER FOR GAS-ENGINES.

1,301,066.

Specification of Letters Patent. Patented Apr. 15, 1919.

Application filed May 11, 1916. Serial No. 96,864.

To all whom it may concern:

Be it known that I, JACOB H. LEIST, a citizen of the United States, residing in the city of Portland, county of Multnomah, and State of Oregon, have invented certain new and useful Improvements in Gasifiers for Gas-Engines, of which the following is a specification.

My invention relates to gasifiers for gas engines, similar to that shown and described in my pending application, filed March 13, 1916, under Serial Number 83,317. I have found by further study and experimental work that I can very materially improve the combustible mixture passing through the carbureter by connecting therewith the overflow pipe of the radiator, whereby a certain amount of vapor from said radiator is conveyed, along with the warm air, through the carbureter, and mixed with the gasoline, distillate or other gas producing fuel, before it goes into the intake manifold of the engine. I prefer to connect a vapor pipe with the overflow pipe of the radiator because this forms the most convenient means of attachment to the radiator, but it will be understood, of course, that any connection from a radiator to the carbureter, whereby to convey vapor from said radiator through said carbureter, is intended to be included as a part of my invention.

In order that others may understand my invention clearly, I have illustrated one practical form thereof in the accompanying sheet of drawings, which I will now describe.

The figure represents a side elevation of a gas engine in dotted lines with my improved gasifier attached thereto, as illustrated in my co-pending application, above referred to, and also showing the overflow pipe of a radiator connected for passing vapor to the carbureter.

In the illustration of the invention here shown, 1 designates the exhaust manifold of a gas engine adapted to be connected as at 2, with an exhaust pipe, not shown, the main body of the engine being indicated in light dotted lines, as is also the intake manifold, 50 designated 3. 4 designates a chamber-form-

ing member extending over and along the exhaust manifold 1, and connected by means of a pipe 5, to the carbureter, which is designated 6. The air which passes through the hood, or member, 4, is heated and conveyed to and through the carbureter 6, in a manner which is clearly understood. 7 designates the radiator, and 8, the overflow pipe of the engine, which pipe, in some cases, extends out through the side of the radiator 60 and down along the outside thereof, as at 9. 10 designates a vapor pipe connected with the overflow pipe of the radiator, and in the present illustration is carried through the hood, or air-heating member 4, above 65 the exhaust manifold of the gas engine so as to discharge the vapor down through the pipe 5, as at 11. This vapor which is warmed during its passage through the hood is mixed with the heated air and thereby 70 greatly improves the explosive mixture resulting, as it is discharged from the carbureter to the intake manifold 3. The vapor pipe can be connected, as at 10^a, with the overflow pipe from the radiator, although 75 it is to be understood that this pipe may be considered as a separate pipe connected into the radiator in any desired position for the purpose of conveying vapor therefrom to the carbureter. Instead of connecting the 80 overflow, or vapor pipe, through the hood, as illustrated, said pipe can be connected directly to the carbureter, as indicated in dotted lines at 12. Drain openings, as 13, would be provided for the escape of water 85 overflowing from the radiator.

I am aware that slight changes can be made in my invention, here shown for purposes of illustration, without departing from the spirit thereof and I do not, therefore, limit the invention to the details here shown, except as I may be limited by the hereto appended claim.

I claim:

In combination with the exhaust member, 95 carbureter and the radiator of a gas engine, an air heating hood mounted over said exhaust member and terminating in a pipe leading to the carbureter of said engine, and a pipe from the radiator extended under 100

said hood along said exhaust member and discharging into the air pipe leading to said carbureter, whereby water, or vapor, from said radiator is heated and converted into steam as it passes along adjacent said exhaust member and under said hood, substantially as shown and described.

Signed at Portland, Multnomah, county, Oregon, this 5th day of May, 1916.

JACOB H. LEIST.

In presence of:

I. M. GRIFFIN,
J. C. STRENG.
